Des. 194,603
Patented Feb. 19, 1963

194,603

ELECTRICAL CONNECTOR APPLICATOR

Herbert Rosengren, Woodcliff Lake, N.J., and Milton D. Ross, Harrisburg, Pa., assignors to AMP Incorporated, Harrisburg, Pa.

Filed Oct. 16, 1961, Ser. No. 67,101

Term of patent 14 years

(Cl. D26—1)

FIGURE 1 is a perspective view of an electrical connector applicator, showing our new design.

FIGURE 2 is a top plan view.

FIGURE 3 is a side elevational view, the side opposite being substantially a mirror image thereof.

FIGURE 4 is a front elevational view.

We claim:

The ornamental design for an electrical connector applicator, specifically as shown and described.
